UNITED STATES PATENT OFFICE.

EVERETT S. CAMERON, OF WEST HAVEN, CONNECTICUT.

OIL-COOLING SYSTEM FOR EXPLOSIVE-ENGINES.

1,384,234.

Specification of Letters Patent. Patented July 12, 1921.

Application filed April 29, 1920. Serial No. 377,508.

To all whom it may concern:

Be it known that I, EVERETT S. CAMERON, a citizen of the United States, residing at West Haven, in the county of New Haven 5 and State of Connecticut, have invented a new and useful Improvement in Oil-Cooling Systems for Explosive-Engines; and I do hereby declare the following, when taken in connection with the accompanying drawings and the characters of reference marked thereon, to be a full, clear, and exact description of the same, and which said drawings constitute part of this application, and represent, in—

15 Figure 1, a schematic view of an oil-cooling system embodying my invention;

Fig. 2, a plan view thereof;

Fig. 3, a view in front elevation of the pressure radiator thereof;

20 Fig. 4, a broken view thereof in vertical section on the line 4—4 of Fig. 3;

Fig. 5, a view thereof in transverse section on the line 5—5 of Fig. 4;

Fig. 6, a broken detail view partly in plan 25 and partly in section showing the right-hand group of tubes of the radiator.

My invention relates to an improved oil-cooling system for explosive engines, the object being to provide an explosive engine, 30 of whatever type and however used, with simple, light, durable, and efficient means for cooling the oil employed to lubricate its working parts.

With these ends in view, my invention 35 consists in an oil-cooling system characterized by having a pressure-radiator in which the oil is cooled and from which it is forced where required to lubricate the working parts of the engine. My invention further

40 consists in an oil-cooling system characterized by a pressure radiator in which the oil is cooled and from which it is forced where required to lubricate the working parts of the engine, in combination with means 45 whereby the radiator may be cut out of the system without interfering with the delivery of oil under pressure to the working parts of the engine.

My invention further consists in an oil-cooling system having certain details of construction as will be hereinafter described 50 and pointed out in the claims.

In carrying out my invention, as herein shown, I employ a motor-driven, high-pressure oil-pump 6 of any approved construc-

tion and herein shown as located at the rear end of the lower half or oil-pan 7 of the crank-case of the engine. The main body of oil is located in this pan which constitutes the oil reservoir of the engine. The upper 60 part of the crank-case, however constructed, is indicated by the reference numeral 8. From the pump 6, the oil is forced under pressure through a small pipe 9 to a three-way valve 10 of any approved construction. 65 A connecting pipe 11 leads from the three-way valve 10 to a T 12 from which right and left inlet-pipes 13 and 14 lead to the opposite ends of an oil-cooling radiator supported upon the forward end of the chassis 70 15 at a point directly in front of the engine where the water-cooling radiator of water-cooled engines is commonly located. Check-valves 16 and 17 are located in the inlet-pipes 13 and 14 at their respective connections with the lower end of the radiator, as shown in Fig. 2.

As herein shown, the radiator consists of a vertically arranged frame 18 resting at its lower end upon the chassis 15 and consisting of groups of relatively small, vertically arranged oil-cooling pipes or tubes 19 opening at their upper and lower ends into chambered heads 20 and 21, as shown in Fig. 5, these heads being furnished with baffle-plates 22 which provide for the deflection of the oil through the tubes in which it is forced to travel up and down so as to circulate in the radiator. The arrangement of the tubes in groups is a matter of detail and 80 will depend upon the size of the radiator and the character of the work to be performed. As herein shown, the radiator is made up of five groups of four tubes each, 85 but obviously, this arrangement may be varied as desired.

In the radiator shown, the oil entering the radiator through the inlet-pipes 13 and 14 will pass upward into the compartments 23 and 24 in the lower chambered head 21, will rise through the four tubes 19 of the outer groups of tubes into the compartments 25 and 26 of the chambered upper head 20 and flow thence downward through the four tubes 19 of each of the intermediate groups of tubes into the compartment 27 of the head 21. From compartment 27, the oil will flow upward through the four tubes 19 of the central group, whereby it will be discharged into the compartment 28 of the up- 100 105 110

per head 20. From the compartment 28 the oil will be led into a short pipe 29 mounting a combined oil-pressure gage and thermometer of any approved construction, and herein indicated by the reference numeral 30. This device serves to inform the user of the engine of the pressure under which the oil leaves the radiator and its temperature at any given moment. From the pipe 29, an outlet-pipe 31 leads downward back of the radiator to a shut-off valve 32, thence through a pipe 33 to a T 34 connected by an auxiliary-pipe 35 to the three-way valve 10 before mentioned. An oil-distributer pipe 36 leads from the T 34 to the working parts of the engine from which the oil falls back into the oil-pan 7 constituting the lower part of the crank-case and forming the oil reservoir of the engine, as already described. It will be understood that all of the several pipes and tubes herein described are adapted in size with relation to each other and to the capacity of the pump to maintain the oil under pressure at the time it leaves the radiator and is delivered to the working parts of the engine.

In the use of my improved system, the oil is forced by the circulating pump 6 forward through the pipe 9 by which it is delivered to the inlet-pipes 13 and 14, passing thence through the check-valves 16 and 17 into the radiator through which it circulates and in which it is cooled by the free movement of air around the tubes which may or may not be exposed to the action of a fan. From the radiator, the cooled oil passes through the outlet-pipe 31 to the distributer-pipe 36 by which the oil, still under pressure, is carried to and forced into the moving parts of the engine. In case the radiator is damaged or becomes deranged, or it is desired for any reason to cut it out of the system, it is only necessary to operate the three-way valve 10 so as to cause the entire body of oil fed through the pipe 9 to be diverted through the pipe 35 to the T 34 and directly into the distributer-pipe 36.

To prevent the oil from being forced into the pipe 31, the shut-off valve 32 is closed.

It will be seen from the foregoing that under my improved system, the oil employed for the lubrication of the engine is forced under pressure into an oil-cooling radiator from which the oil is delivered under pressure to the working parts of the engine, and furthermore, that the radiator, if deranged, may be cut out of the system without interfering with the action of the pump in delivering oil to the working parts.

I claim:

1. An oil-cooling pressure system for explosive engines, having an engine, an oil-tank therefor, a pressure pump, a pressure radiator to which the oil is pumped under pressure from the tank and from which it is delivered under pressure, oil-distributing means leading from the radiator to the working parts of the engine to which the oil is supplied under pressure, and means in the system for cutting out the radiator without interfering with the pumping of the oil under pressure to the working parts of the engine.

2. An oil-cooling pressure system for explosive engines, having an engine, an oil-tank therefor, a pressure pump, a pressure radiator into which the oil is pumped from the tank and from which it is delivered under pressure, oil-distributing means leading from the radiator to the working parts of the engine, check-valves located in the connections between the radiator and the pump, and a three-way valve also located in the said connections and providing for cutting the radiator out of the system without interfering with the pumping of the oil under pressure to the working parts of the engine.

In testimony whereof, I have signed this specification in the presence of two subscribing witnesses.

EVERETT S. CAMERON.
